TWO-COLOR ROCKING MAGAZINE

Richard G. Turner, Worcester, Mass., assignor to
 Crompton & Knowles Loom Works, Worcester,
 Mass., a corporation of Massachusetts

Application March 5, 1937, Serial No. 129,245

12 Claims. (Cl. 139—232)

This invention relates to improvements in weft replenishing looms and it is the general object of the invention to provide simplified mechanism for presenting for transfer a plurality of distinctive types of reserve bobbins.

In the weaving of certain fabrics in automatic looms it is necessary to provide different types of weft in order that patterned effects may be woven crosswise of the fabric. This has been accomplished heretofore in a so-called stationary magazine in which are mounted stacks of distinctive reserve wefts over releasing mechanism in the form of cradles, and color controls have been necessary to select the correctly colored weft. It is an important object of my present invention to eliminate the cradles and their controls as heretofore employed and provide a rocking magazine having a plurality of stacks of reserve bobbins so arranged that the lowest bobbin of each stack can be moved to transfer position by rocking of the magazine.

It has been proposed heretofore to use rocking magazines, but in most instances mechanisms of this type have oscillated with each shifting of the shuttle boxes at the opposite end of the loom with the result that the bobbins are subject to a vibration which interferes with proper thread control. It is a further object of my present invention to provide a loom wherein the magazine is normally at rest and is rocked only at the time of transfer. In this connection it is a further object of my invention to have the magazine normally placed for transfer of one color so that when that color is called there is no rocking of the magazine, the latter rocking only when some other color is called.

It occasionally happens that a shuttle will fail to be properly boxed on a transferring beat of the loom, in which case it is necessary to revoke the previous setting of the magazine and transfer. It is a still further object of my invention to set the magazine for transfer by a train of mechanism including a connection which first operates to set the magazine and then operates to break the train for the purpose of permitting revocation of the transfer without damaging the control connections for the magazine.

Certain features of my invention are more particularly adaptable for use with so-called flat bobbins the weft mass of which is non-circular in transverse cross section, the horizontal axis for the section being greater than the vertical axis. When such bobbins are used provision must be made for presenting them properly positioned for cooperation with the transfer arm. When in

transfer position the greater transverse axis of the bobbin barrel should preferably be inclined downwardly and forwardly at a given angle determined by the axis of the transerrer and the location of the shuttle under the magazine. In a rocking magazine this angular relation will be subject to change due to the angular motion of the magazine as a whole, and it is a further object of my further invention to provide guides and supports for the various stacks of bobbins so proportioned and positioned as to present a bobbin of the flat type in correct transfer position for the different angular settings of the magazine.

While the magazine illustrated is shown adapted for flat bobbins yet certain features of my invention are not limited to such bobbins.

With these and other objects in view which will appear as the description proceeds, my invention resides in the combination and arrangement of parts hereinafter set forth.

In the accompanying drawings, wherein a convenient embodiment of my invention is set forth,

Fig. 1 is an end elevation of a portion of a loom having my invention applied thereto, the lay, shuttle box and shuttle being shown in section,

Fig. 2 is an enlarged detailed end elevation of the upper left hand part of Fig. 1,

Figs. 3 and 4 are operating views of the lower portion of the magazine showing the latter in different positions,

Fig. 5 is a plan view of a flat bobbin of the type usable in the magazine illustrated,

Fig. 6 is an end elevation of parts of the magazine taken from the center of the loom, and

Fig. 7 is a diagrammatic front elevation of a loom having my invention applied thereto.

Referring to the drawings, I have shown a loom frame 10 and a lay 11 movable backwardly and forwardly by a top or crank shaft 12. The lay is mounted on swords 13 pivoted at 14 and carries a shuttle box 15 to receive either of two different shuttles, one active shuttle S being shown in Fig. 1. These shuttles are rendered active alternately by shuttle box mechanism shown generally at 16 in Fig. 7 located at that side of the loom opposite the magazine to be described.

A bottom shaft 20 running half as fast as the top shaft carries a grooved cam 21 to move a roll 22 on actuator lever 23 rocked regularly by the cam. To the forward end of the lever there is pivoted a lifting dog 24 which normally has an idle ascending motion on those beats of the loom when transfer is not called. Lever 23 rocks on a fixed stud 25 on which there is also pivoted a sec-

ond or lifting lever 26 normally at rest and having the rear end thereof provided with a laterally projecting stud 27. Lever 26 has mounted thereon a solenoid 28 and a color selector mechanism designated generally at C including two control fingers 29 and 30. These fingers are normally out of the path of a small cam 31 on the dog 24, but when one or the other of the fingers is set for transfer and is over cam 31, rising of the forward or left hand end of lever 23 as viewed in Fig. 1 will cause the dog to be cammed by the set finger registering therewith into lifting relation with a shoulder 26' on the front end of lever 26. When this occurs a rod 32 pivoted to lever 26 is raised for a purpose to be described.

The setting of the fingers 29 and 30 is effected by a weft detector D which in the present instance is of the electrical type and suspended from parallel links 33 hung from a fixed support 34 on a stationary transfer stud 35. The weft detector may be of the type shown in patent to Payne No. 1,924,197 and a circuit is closed through the detector when the weft W on the active bobbin B becomes substantially depleted. At this time the following circuit will be closed; battery P, wire 36, detector D, wire 37, solenoid 28, and wire 38 connected to the battery. Current flowing in this circuit will energize the solenoid and cause the latter to set one or the other of the fingers 29 or 30 for control of the dog 24.

The fingers are mounted on a carriage 40 movable longitudinally on lever 26 in time with some part coordinated with the shifting shuttle boxes at the opposite end of the loom. As shown herein this part is a lever 41 connected to a link 42 and flexible cable 43 which extends across the loom and is connected to drop box mechanism 16, see Fig. 7. Lever 41 pivots about a stud 45 on a stationary holder 46 secured to the stud 25, and the upper part of lever 41 is connected to the slide 40 by means of a rod 47. Passing through part of the lever is a hook 48 the lower end of which is adapted for cooperation with the stud 27 for certain of the transfers. The hook is secured to the lower end of rod 49 which is depressed by the rocking of lever 26 when the hook is under stud 27. A tension spring 50 is connected to the holder 46 and lever 41 to hold the latter yieldingly in the position shown in Fig. 1. The lever 41 may be rocked in a right hand direction around stud 45 against the action of spring 50.

The matter thus far described, with the exception of the mounting for the weft detector, may be the same as that heretofore used and shown more fully in prior Patents Nos. 2,054,192 and 2,054,173. A distinction is to be found between these patents and my present invention, however, in that there is but one hook 48, the reason for which will be pointed out hereinafter.

Referring more particularly to my invention, I provide a magazine M pivoted on a fixed stud 60 and having front and back compartments 61 and 62, respectively, for reserve bobbins. A lever 63 with a fixed pivot 64 is attached to rod 49 and also to a forwardly extending rod 65 carrying a spring 66 and passing through a stud 67 against which the spring presses, see Fig. 6. The rear end of the spring is positioned by a collar 68 on the rod 65 and a second collar 69 on the rod 65 engages the stud 67 to limit forward expansion of the spring.

The magazine includes an inner plate 75 carrying stud 67 and having front and back bobbin butt compartments 76 and 77, respectively, and the magazine also has two outside end plates 78

and 79 which are in front of and behind the axis of the magazine, respectively. Tie rods 80 may be employed to secure the end plates to the inner plate to cause the plates to rock as a unit about the stud 60. The rear end plate 79 has a smooth weft thread guide surface 81 along the front edge thereof, while the front plate 78 has a similar surface 82 along the forward edge thereof. The thread guides' surfaces so disposed facilitate loading of bobbins into the magazine.

While my invention can be employed in connection with the usual type of bobbin having a cylindrical barrel, yet I have illustrated the magazine as adapted for use with the so-called flat bobbin shown in Fig. 5 and having a barrel F the horizontal transverse axis of which is greater than the vertical axis. The bobbin has a head 85 provided with rings 86 and having parallel or slab surfaces 87, one of which shows in Fig. 5.

The front end plate 78 has a bobbin tip receiving groove 90 slightly wider than the thickness of the bobbin tip, and this groove curves rearwardly toward an enlargement 91. As the bobbins descend they turn as their tips move along the curved part and the major transverse axis of the bobbin barrel approaches the horizontal. When in this position the bobbin tip rests on a yieldable tip support 92 pivoting about a stud 93 carried by the plate 78. A leaf spring 94 mounted on a plate 78 pushes outwardly on the top of the support 92 and holds a supporting ledge 95 with a flat upper surface 96 yieldingly under the bobbin tip. At transfer the ledge moves outwardly in a direction longitudinally of the axis of the bobbin being transferred. In a similar manner, rear end plate 79 has a bobbin tip groove 97 which curves forwardly to guide a descending bobbin over and onto a flat top surface 98 of a yielding support 99 pivoted on stud 100 and positioned by leaf spring 101 similar to spring 94.

The surfaces 96 and 98 are not parallel, the angular distance between their planes being substantially equal to the angle through which the magazine rocks. The reason for this relationship is due to the desirability of having the major transverse axes of the bobbin barrels at the same angle with respect to the horizontal when the bobbins on the supports are in transfer position.

The yielding supports for the bobbin heads or butts are shown in Figs. 4 and 6. The front support 105 has an upper guide surface 106 for the bobbin rings and a depending lip 107 to guide the bobbin head during transfer. Support 105 is pivoted at 108 to the inner magazine plate 75 and is held yieldingly in rear position by spring 109. The distance between lip 107 and an intermediate guide 110 integral with plate 75 is less than the diameter of the rings, and at transfer the support rocks forwardly to allow the lowest bobbin in compartment 76 to be moved into the shuttle. The rear end plate has a butt support 112 with a lip 113 and is pivoted at 114 and held yieldingly forward by spring 115. Surface 116 inclines forwardly and downwardly and lip 113 is normally near enough to guide 110 to hold the lowest bobbin in compartment 77. Since the bobbin rings are circular it is not necessary that surfaces 106 and 116 sustain the same relationship as that described for the tip supports.

The transerrer arm 120, shown more particularly in Figs. 1, 2 and 4, is pivoted on stud 35 and has pivoted thereto at 123 a carrier 122 to which is bolted a transfer latch 124 with a notched rear end 125 for engagement with a bunter 126 on the lay 11.

The forward or left hand end of the carrier 122 as viewed in Fig. 2 is pivoted to rod 130 having a rod head 131 slotted as at 132 to receive a stud 133 on lever 134 which moves about a stub shaft 135 rotatable in a magazine supporting bracket 136. The lower end of the latter is mounted on the loom frame and the upper end thereof is attached to the loom arches, as suggested in Figs. 1 and 2. An arm 137 secured to the inner end 10 of the shaft 135 has a connection 138 with a link 139 moving about an axis 140 on the bracket 136, and a spring 141 tends to hold the arm 137 against one of two spaced stops 142 so positioned as to hold the lever 134 yieldingly locked in either of two extreme positions.

A shuttle feeler 143 is pivoted on step shaft 144 and is connected by a link 149 to the lever 137 of the yielding lock of which spring 141 is a part. This shuttle feeler is normally forward out of 20 the path of the shuttle when the transfer latch 124 is down or in non-transfer position, and can be set along shaft 144 the desired distance, depending upon the length of the shuttle and the amount of shuttle rebound permissible.

The rear end 145 of lever 134 carries a laterally extending pin 146 to enter a hook 147 on the upper end of a rod head 148 secured to the rod 32 already described. A lifting shoulder 150 on rod head 148 is spaced from the hook 147 to define an opening 151 through which the pin 146 may pass. A light spring 152 has its forward end connected to the transfrerer arm while the rear end connected to a return lever 153 pivoted to the transfrerer arm at 154 and engaging the 35 rear part of head 148. The lower front part of the head has an inclined cam 155 to engage a stud 156 on the transfrerer arm for the purpose of moving head 148 rearwardly at transfer to disconnect the head from the pin 146. The customary torsion spring 157 acts in the usual manner to hold the transfrerer arm up, as shown in Fig. 2. A holding surface 160 on the head extends downwardly from area 155 for a purpose to be described.

Fig. 6 shows means to control the rocking movements of the magazine. A rear stop screw 165 adjustable vertically in bracket 136 engages a lug 166 of the inner magazine plate 75 behind the magazine axis, while a second screw 167 in the bracket engages a second lug 168 of the plate 75 in front of the axis. A return spring 170 is located between the magazine and bracket and tends to hold the magazine yieldingly in rear position. This spring is weaker than spring 66 50 and yields to the action of the latter when the magazine is to be rocked. If the rod 65 continues to move after stop screw 167 arrests the magazine, spring 66 yields to prevent breakage. Spring 170 acts through rods 65 and 49 to lift hook 48 after 55 lowering thereof by stud 27.

In operation, the shuttle boxes at the left hand end of the loom will shift in response to the pattern mechanism not shown to rock lever 41 from one extreme position to the other. This rocking 60 occurs before the active shuttle reaches the box under the magazine and therefore the color control mechanism C will have one or the other of the control fingers 29 or 30 in register with the cam 31. Spring 170 holds the magazine so that 65 the lowest bobbin in the rear stack will be over the shuttle S. Rod 32 and latch 124 will be down and the shuttle feeler will be forward. When the lay moves forwardly with an empty shuttle under the magazine the detector D will close the 70 previously traced circuit and assuming that the

shuttle corresponds to the front stack of bobbins in the magazine, the control element 29 will be set for transfer. The shuttle will be picked to the opposite or box end of the loom and if it is to remain active the slide 40 will remain in the forward position shown in Fig. 1 so that when the dog 24 rises, the finger 29 will engage cam 31 to direct the dog under shoulder 26.

Lever 26 then rocks to lower pin 27 and hook 48 which under these conditions is under pin 27, 10 and lever 63 turns to move the magazine in a left hand direction as viewed in Fig. 1 to place the lowest front bobbin for transfer. Rocking of lever 26 also raises rod 32 to force shoulder 150 against stud 146 and rock lever 134 in a left hand direction to raise transfer latch 124 into the path of the bunter 126, see Fig. 6. The turning of shaft 135 with lever 134 also moves the shuttle feeler 143 rearwardly into shuttle feeling position. As the connection 138 rises to a point above a line 20 joining centers 135 and 140, spring 141 will give lever 134 a quick advance motion to move the pin 146 away from shoulder 150.

At about this time surface 155 of the head 148 engages the stud 156 on the transfrerer arm and 25 moves the head rearwardly against the action of spring 152. Stud 146, being opposite the opening 151, passes through the latter as the head 148 moves rearwardly. In this way the train of connections between the lever 26 and 30 those parts controlled by rocking of shaft 135 is temporarily broken.

As the lay advances the bunter will engage the latch to rock the transfrerer arm 120 and cause the lowest bobbin in the front compartment 35 of the magazine to pass into the shuttle S. It will be understood from Fig. 2 that the bobbin which is in transfer position at this time has the transverse axis of its barrel inclined upwardly and rearwardly and as the transfrerer descends 40 the bobbin will turn on its axis so as to reach the fully transferred position indicated in Fig. 2 with the major transverse axis of the bobbin barrel horizontal.

During transfer the bobbin head support 45 corresponding to the bobbin being transferred will move against its spring away from the intermediate bobbin guide 110 and the corresponding tip support will swing outwardly in a direction longitudinally of the axis of the bobbin 50 against the action of the associated leaf spring. For further details of the transferring action with respect to flat bobbins, reference may be had to my copending application Serial No. 97,967. 55

During the time that the lay is moving latch 124 forwardly stud 156 will move down along surface 168 to maintain head 148 in rear position. As the lay nears front position it strikes the shuttle feeler to reset the latter in forward 60 position, thereby rocking shaft 135 to release the latch 124. Slot 132 permits rocking of lever 134 while the latch is still engaging the lay bunter. During this resetting of lever 134 stud 146 moves through opening 151. 65

As the lay recedes the transfrerer arm will rise under the action of spring 157 and when the stud 156 starts to move up the incline 155, spring 152 will rock lever 153 forwardly to return the head 148 to front position. Further downward 70 movement of rod 32 will cause the hook to be restored to normal engagement with stud 146. The latch 124 then drops back to normal position by gravity and the parts are restored to the position of Fig. 2 for the next transfer. After transfer 75

is completed and the transerrer arm is raised to clear guide 110, cam 21 will act to permit spring 170 to rock the magazine back to normal position. It is to be understood that the cam 21 5 must maintain the magazine in position throughout the transfer, and it is for this reason that the pin 146 must be capable of disengagement with head 148 should transfer be revoked.

Should the shuttle not be properly boxed it is 10 necessary to revoke the transfer and this will be accomplished by the forward motion of the shuttle feeler which will rock shaft 135 with resultant dropping of the latch 124 out of the path of the bunter on the lay. The rocking of lever 134 under these conditions will move the stud 146 along a downwardly and forwardly extending arcuate path, but at this time the rod head 148 is in rear raised position, hence said stud 146 will move in front of shoulder 150.

20. If transfer is to be from the rear stack the color control C will be moved so that finger 30 is in register with cam 31 and hook 48 will move rearwardly from under stud 27. Under these conditions the same operation previously described takes place with the exception that hook 48 will not be lowered, since the magazine is not to be rocked.

The particular means for breaking the connection between the lever 26 and the transfer 30 mechanism, including the head 148 and the space 151 through which the stud 146 passes, is not claimed herein but is made the subject matter of a separate application filed on March 17, 1937, by Cederlund Serial No. 131,430.

35. Having thus described my invention it will be seen that changes and modifications may be made therein by those skilled in the art without departing from the spirit and scope of the invention and I do not wish to be limited to the details 40 herein disclosed, but what I claim is:

1. In a weft replenishing loom operating with a lay and having a plurality of weaving shuttles any one of which may become active, a rocking magazine normally stationary and having groups 45 of distinctive reserve bobbins, one group for each weaving shuttle, an actuating lever having a working stroke on alternate beats of the loom, an operating lever normally at rest, transfer mechanism to be set for cooperation with the lay to effect transfer by the operating lever when the latter moves, force transmitting control means 50 for the magazine to have transmitting and non-transmitting positions relatively to the operating lever, selector mechanism to assume a plurality of positions depending upon which weaving shuttle is active and connected to the transmitting control means to move the latter relatively to the operating lever, means operative upon exhaustion of weft in an active weaving shuttle 55 to connect the actuating and operating levers together and cause the actuating lever to move the operating lever, the latter thereupon setting a transfer mechanism for operation by the lay and moving the force transmitting means to effect 60 rocking of the magazine when the transmitting means is in transmitting position relatively to the operating lever to place one of the groups in transfer position, and means to hold the magazine with another of the groups in transfer position when the transmitting means is in non-transmitting position relatively to the operating lever.

2. In a weft replenishing loom having a lay and operating with a plurality of weaving shuttles any one of which may become active, a 75

rocking magazine normally stationary and having a group of reserve bobbins for each weaving shuttle, yielding means normally holding the magazine at rest with one of the groups in transferring position relatively to the lay, an actuating lever having a working stroke on alternate beats of the loom, an operating lever normally at rest, transfer mechanism, connections between the operating lever and the transfer mechanism to set the latter for operation by the lay when the operating lever moves, force transmitting control means for the magazine to have transmitting and non-transmitting positions relatively to the operating lever, selector mechanism connected to the force transmitting control 10 means and effective to give the latter either transmitting or non-transmitting positions depending upon which weaving shuttle is active, and means depending upon weft exhaustion in an active shuttle to connect the actuating and operating levers and cause the latter to be moved by the actuating lever, movement of the operating lever setting the transfer mechanism for operation by the lay and operating the force transmitting means control when the latter is in transmitting position relatively to the operating lever to rock the magazine and cause another group thereof to move to transfer position relatively to the lay.

3. In a weft replenishing loom having a lay 30 and operating with a plurality of weaving shuttles any one of which may become active, a rocking magazine normally stationary and having a group of reserve bobbins for each weaving shuttle, a primary yielding means to hold the magazine normally at rest with one group of reserve bobbins positioned for transfer, a regularly moving lever having an operating stroke every alternate beat of the loom, an operating lever normally at rest, force transmitting control means 35 to connect the operating lever to the magazine, selector mechanism to move the force transmitting control means to transmitting and non-transmitting positions relatively to the operating lever, a secondary yielding means stronger than the primary yielding means forming part of the force transmitting control means to be located between the magazine and the operating lever, and means dependent upon exhaustion of weft in an empty shuttle to connect the regularly moving lever to the operating lever to cause movement of the latter, movement of the operating lever when the force transmitting means is in transmitting position causing the secondary yielding means to overcome the primary yielding 50 means and rock the magazine to position another group of reserve bobbins for transfer position.

4. In a weft replenishing loom having a lay, transfer mechanism, a magazine having a plurality of groups of reserve bobbins in the magazine, a support on which the magazine is pivoted, each reserve bobbin having a transverse dimension measured in one direction greater than the transverse dimension measured at right angles to said direction, and support means for each group 60 movable with the magazine to place a reserve bobbin of the corresponding group in position for transfer, each support means when in transfer position effective to position the reserve bobbin in engagement therewith with the greater transverse dimension of said reserve bobbin bearing a given angular position with respect to the transfer mechanism.

5. In a weft replenishing loom having a lay, a multicolor magazine to hold a plurality of re- 75

- serve bobbins, a fixed support constituting a pivot for the magazine around which the latter rocks to position the groups for transfer one at a time, a reserve bobbin support for each group 5 movable with the magazine, each reserve bobbin having a transverse dimension in one direction greater than the transverse dimension measured at right angles to said direction, means to rock the magazine to place either support in transfer 10 position, and means on the supports to hold the reserve bobbins in engagement therewith with the greater transverse dimension of the reserve bobbins oblique with respect to each other, the angular distance between the greater dimensions 15 of the reserve bobbins in engagement with the supports being substantially equal to the angle through which the magazine rocks to move one group out of and another group into transfer position.
- 20 6. In a weft replenishing loom, a multicolor magazine having a pair of stacks of reserve bobbins, a support on which the magazine is pivoted, each bobbin having a relatively long transverse axis measured in one direction, a support 25 for each group of bobbins, each support holding the lowest bobbin in the corresponding group in readiness for transfer, means to rock the magazine to place the lowest bobbin of either stack in transfer position, a transerrer arm movable 30 along a given path to effect transfer, and means on each support to engage the bobbin resting thereon and determine the angular position of said transverse axis of said bobbin, said means on the two supports being oblique with respect to 35 each other by an amount approximately equal to the angular distance through which the magazine rocks when moving the lowest bobbin in one stack away from transfer position and the lowest bobbin of the other stack into transfer position 40 with respect to the given path.
7. In a weft replenishing loom, a magazine having two stacks of reserve bobbins, each bobbin having a relatively long transverse axis measured in one direction, a pivot for the magazine about 45 which the latter swings, a transerrer moving along a given path, means to rock the magazine so that the lowest bobbin in either stack can be moved to transfer position in said path, and means to hold the lowest bobbins of the stacks 50 with their said transverse axes oblique with respect to each other by an angle substantially equal to the angle through which the magazine rocks about the pivot therefor when moving the lowest bobbin of one stack away from said path 55 and the lowest bobbin of the other stack into said path.
8. In a weft replenishing loom, a magazine having a pair of groups of reserve bobbins each of which is non-circular in transverse section with 60 the major diameter exceeding other diameters, a transerrer moving in a given path to effect transfer, a support on which the magazine is pivoted, means to rock the magazine so that the lowest bobbin of either group can be placed in said path, and a support for each group, each support holding the lowest bobbin of the corresponding group with the major diameter thereof oblique with respect to the major diameter of the bobbin 65 resting on the other support by an angle substantially equal to the angle through which the 70 magazine rocks to move one bobbin out of and the other bobbin into said given path.
9. In a weft replenishing loom, a magazine having a pair of groups of reserve bobbins each of which has a transverse major diameter exceeding other diameters, a transerrer moving in a given path, a support on which the magazine is pivoted, means to rock the magazine angularly through a given angle to move the lowest bobbin of one group out of said path and the lowest bobbin of another group into said path, and means to support the lowest bobbins of the group with their major diameters oblique with respect to each other by substantially the same angle as that through which the magazine rocks. 15
10. In a weft replenishing loom, a magazine having a pair of groups of reserve bobbins each of which has a tip with flattened opposite sides, a guideway for each group to receive the tips of the corresponding bobbins and prevent substantial angular motion thereof, a support at the bottom of each group having a flattened surface to engage the under side of a reserve bobbin resting thereon, the flattened surfaces of the supports being oblique with respect to each other, a transerrer 20 moving in a given path, a support on which the magazine is pivoted and means to rock the magazine through a given angle to place a bobbin resting on either support in said path, the surfaces of the supports being oblique with respect to 25 each other by substantially said given angle.
11. In a weft replenishing loom, a magazine having a pair of groups of reserve bobbins each of which has a major transverse axis exceeding all other axes, a pivot for the magazine, a pivoted 30 transerrer moving in a given path, a shuttle of greater width than height and having the width thereof substantially horizontal when in transfer position, a support for the lowest bobbin of each group, means to rock the magazine so that 35 the lowest bobbin of either group will be in the path of the transerrer, each support constructed to hold the bobbin resting thereon when in transfer position with its major axis oblique with respect to a horizontal line by substantially the 40 same angle through which the transerrer moves along the path thereof when in engagement with a bobbin being transferred.
12. In a weft replenishing loom, a magazine having a pair of groups of reserve bobbins each of which bobbins has a major transverse axis exceeding all other axes, a pivot for the magazine, a pivoted transerrer moving in a given path, a shuttle of greater width than height and having the width thereof substantially horizontal when 45 in transfer position, a support for the lowest bobbin of each group, means to rock the magazine so that the lowest bobbin of either group will be in the path of the transerrer, the supports constructed to hold the bobbin resting thereon when 50 in transfer position with its major axis oblique with respect to a horizontal line by substantially the same angle as that through which the transerrer moves along the path thereof when in engagement with a bobbin being transferred, the 55 major axes of the bobbin resting on the supports being oblique with respect to each other by substantially said angle, to the end that rocking of the magazine will place the bobbin located in said path in correct angular position for transfer. 70
